APRON

Flora L. Rouleau, Oakland, Calif.

Application March 21, 1932. Serial No. 600,252

4 Claims. (Cl. 2—48)

The object of this invention is to provide an apron which in one size may be worn by stout as well as slender persons and will readily conform to the figure so as to fit neatly and present 5 an attractive appearance. The invention also has for its object the provision of supporting means which will avoid the necessity of slipping the apron over the head of the wearer and will retain the apron upon the body of the wearer 10 and which may be readily adjusted to obtain a reasonably snug fit and prevent the apron dropping from the figure under all conditions. Other objects of the invention will appear incidentally in the course of the following description, and 15 the invention resides in certain novel features which will be particularly defined in the appended claims.

In the accompanying drawings, Figure 1 is a front elevation of an apron embodying the present invention,

Fig. 2 is a rear elevation illustrating the manner of securing the apron upon the wearer,

Fig. 3 is a view similar to Fig. 2 but showing a different adjustment of the supporting means,

Fig. 4 is an elevation showing a modification,

Fig. 5 is a detail section on the line 5—5 of Fig. 3,

Fig. 6 is an enlarged detail perspective view showing a clasp which may be employed,

Fig. 7 is a detail view of the apron-engaging hook which is provided at the center of the supporting strap,

Fig. 8 is a similar view of the hook which is provided at the end of the supporting strap,

Fig. 9 is an enlarged detail section on the line 9—9 of Figure 8,

Fig. 10 is a detail perspective view of one end of the supporting strap.

The apron may be constructed of any material 40 and is preferably a square, indicated at 1, obtained by cutting a square decorative table cloth into quarters, each quarter forming one apron. As illustrated in the drawings, the sheet of material or apron is applied to the figure by being 45 suspended with one corner at the throat portion of the wearer, as shown most clearly in Fig.

1. When the apron is suspended at one corner, diagonally opposite corners will, of course, be located at the sides of the apron and these corners may be conveniently formed into pockets 50 by being rolled or folded over onto the face of the apron and then stitched along their lower edges, as shown at 2, the upper edges of the folded portion being left free so as to form the 55 open top of a pocket 3, as will be understood

upon reference to Fig. 5. In the form of the invention shown in Figs. 1, 2 and 3, an eyelet 4 is fastened in the apron at the upper corner of the same and similar eyelets are secured adjacent the upper edges of the apron at points 60 between the upper corner and the pockets, as indicated at 5. A supporting strap 6 of any suitable material is provided and is folded at a point midway its ends, as shown in Figs. 1 and 7, and at the fold is secured a hook 7 which is 65 adapted to engage in the eyelet 4 at the upper corner of the apron. Similar hooks 8 are attached to the ends of the supporting strap and are adapted to engage in the respective eyelets 5, as shown and as will be understood. 70

The hooks are fastened to the middle fold and to the ends of the strap by twin rivets or pins 9 inserted through the ends of the respective hooks and through the strap, the pins or rivets being carried by a reinforcing metal band 75 10 of light sheet metal which overlies the attaching eyes of the hook, as shown in Figs. 7, 8 and 9. To further reinforce the support for the end hooks, the end of the strap is rolled or folded upon itself, as shown at 11 in Fig. 80 10, to present three or more plies of the material against which the base or eyes of the hook are placed. The plate 10 is then set over the eyes of the hook with the pins passing through the eyes and the plies of the strap, and the pins 85 are upset or clinched at the back of the strap. The hook is thus very firmly secured so that it cannot be easily detached from the strap and the plate forms a stop so that a slid able fastener 90 on the strap cannot slip therefrom.

It will be noted, upon reference to the drawings, that, when the strap is engaged with the apron, it presents two loops through which the arms of the wearer may be inserted so that the portions of the strap at opposite sides of its center, that is to say the two loops, will pass over the respective shoulders of the wearer to suspend the apron thereon and it will not be necessary to pass the apron or any part over the wearer's head. At intervals in the length of one loop or branch of the supporting strap, eyelets 95 12 are secured thereto and upon the other loop or branch of the strap is mounted a clasp 13 which is adapted to engage any one of these eyelets and thereby cause the apron to fit closely to the figure of the wearer, as will be understood upon reference to Figs. 2 and 3. The clasp 13 is preferably slid able upon the supporting strap so that it may be selectively engaged with any one of the eyelets 12, as will be 100 105 110

understood. Should the wearer have a slender figure, the clasp will be engaged with one of the lower eyelets 12 and will thereby draw the sides of the apron closely to the wearer's body and obviously the clasp will be adjusted to engage one of the higher eyelets to fit the apron properly to stouter figures. At points near the central supporting hook, there is provided upon the strap a fixed clasp 14 and a single eyelet 15. The clasp 14 and eyelet 15 need not be used unless the wearer has a very slender figure with slight or drooping shoulders, in which event the clasp 14 will be engaged with the eyelet 15 so that the supporting loops will be brought close together at the back of the neck, as shown in Fig. 3, thereby preventing the loops slipping from the wearer's shoulders.

In Fig. 4 is shown a slight modification in which the apron body 16 is formed from a square of material but the upper corner is cut off and the edge is given a slight curve, as shown at 17, while the upper side edges of the apron body are also slightly curved, as indicated at 18, thereby avoiding excessive width below the neck portion of the apron. This outline will conform to many designs in the cloth better than the pointed bib shown in Fig. 1. In the form shown in Fig. 4, the pockets 19 are deeper than the pockets shown in Figs. 1, 2 and 3 but are formed in substantially the same manner, the pockets in the first described form being defined by folding the corners of the apron body so that the overlapped edges will lie at right angles to the edges of the body while, in the form shown in Fig. 4, the corner portions are so folded that the inner edges will approach more closely to vertical lines. In the form shown in Fig. 4, the supporting strap is divided so that an independent loop is provided for each shoulder and the ends of the loops are permanently attached to the body of the apron by stitching or otherwise, the loops being indicated by the numerals 20.

In all forms of the invention a very simple, light and attractive apron is provided. It may be very easily donned and doffed and, when in position upon a wearer, will very effectually protect the dress or other outer garment. The apron may be easily adjusted to conform to the wearer's figure without any change in the construction of any of the parts and may be produced at a cost within the means of anyone, the mere act of fastening the loops together effecting the desired adjustment. The apron will be furnished in measurements corresponding to the average figure so that fastening the straps at a single point will cause the apron to fit snugly to the waist and shoulders. The loops serve all the functions usually served by neck bands and waist bands and render both bands unnecessary.

It will be understood, of course, that the particular form of clasp or fastening employed is immaterial and any readily manipulated fastenings may be used, the clasp shown and described being illustrative only.

Having thus described the invention, I claim,

1. An apron comprising a sheet of material having its upper side edges diverging downwardly, supporting loops attached to the upper side edges of the body and to the upper end of the same, a plurality of fastening elements secured upon one supporting loop, a fastening element adjustably mounted upon the other supporting loop and selectively engageable in one of the first-mentioned fastening elements, and other fastening elements secured in fixed position upon the respective supporting loops adjacent the top of the apron body to secure the loops at a point adjacent the back of a wearer's neck. 80

2. An apron comprising a sheet of material, 95 coating shoulder straps one of which has both its ends secured to one side of the sheet and the other strap both its ends secured to the other side of said sheet whereby the intermediate portions of the loops are normally separated to permit insertion of the arms through said loops at the front of the wearer, and inter-engaging fastening devices carried by the straps for securing said straps together at the back of the wearer. 100

3. An apron comprising a sheet of material having its upper edges diverging downwardly, supporting loops one of which has both ends thereof secured to one side of the sheet and the other loop having both ends thereof secured to the other side of said sheet whereby the intermediate portions of the loops are normally separated to permit insertion of the arms simultaneously through both loops at the front of the wearer, a plurality of fastening elements secured upon one of the loops, and an adjustable fastening element mounted on the other loop and selectively engageable in the first mentioned fastening elements. 110

4. An apron comprising a substantially square sheet, suspension loops at opposite sides of the vertical diagonal of the sheet, one of said loops having both its ends attached to the marginal portions of the sheet at one side of the diagonal of the sheet and the other loop having both its ends attached to the marginal portions of the sheet at the other side of the diagonal of said sheet whereby the intermediate portions of the loops will be normally separated to permit insertion of the arms through both loops at the front of the wearer, and adjustable separable fasteners on the loops whereby the loops may be made to support the sheet on the wearer and adjust it to the wearer's figure. 120
